US00D807458S

(12) **United States Design Patent** (10) **Patent No.:** **US D807,458 S**
Robinson (45) **Date of Patent:** **** Jan. 9, 2018**

(54) **FLOTATION DEVICE**

(71) Applicant: **The MCR Group, LLC**, Knoxville, TN (US)

(72) Inventor: **Phillip Robinson**, Knoxville, TN (US)

(73) Assignee: **The MCR Group, LLC**, Knoxville, TN (US)

(**) Term: **15 Years**

(21) Appl. No.: **29/580,744**

(22) Filed: **Oct. 12, 2016**

(51) **LOC (11) Cl.** **21-02**

(52) **U.S. Cl.**

USPC **D21/803**

(57) **CLAIM**

I claim the ornamental design for a flotation device, as shown and described.

DESCRIPTION

FIG. 1 is a top perspective view of a flotation device of the new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a rear view thereof; and,

FIG. 8 is a front view thereof.

The evenly broken line (dash-dash) in the figure drawings represents unclaimed environment only and forms no part of the claimed design. The dash-dot broken line represents the boundary of the claim and forms no part of the claimed design.

1 Claim, 6 Drawing Sheets
